UNITED STATES PATENT OFFICE.

SIDNEY A. HARTMANN, OF ST. LOUIS, MISSOURI.

DETERGENT.

1,387,153.

Specification of Letters Patent. Patented Aug. 9, 1921.

No Drawing. Application filed June 30, 1919, Serial No. 307,603. Renewed June 24, 1921. Serial No. 480,192.

To all whom it may concern:

Be it known that I, SIDNEY A. HARTMANN, a citizen of the United States, residing at the city of St. Louis, in the State of Missouri, have invented certain new and useful Improvements in Detergents, of which the following is a specification.

This invention is an improved detergent for the purpose of cleaning and removing spots from textile fabrics and the like. In actual use, it has been found much more efficient than others now in common use and, also, to be free from objections present in them. This compound is noninflammable, nonexplosive, and its odor is unoffensive. It will not injure the most delicate cloth or similar fabric nor remove the fine hair on satin. It does not injure the leather when used to clean white polished-kid shoes. It not only acts more efficiently as a cleanser, but performs the cleansing operation more quickly than similar articles heretofore known. It readily dissolves grease and oil, and can be used for removing grease and oil from the hands of autoists, mechanics, and others, as it does not injure the skin. It can be diluted and then used to wash the surplus oil and grease from automobile parts. It will, also, dissolve paint.

It is cheap to manufacture, not only on account of its ingredients, but also because no costly apparatus is needed for that purpose. A bucket, tub, or vat is all that is necessary in order to make it.

This detergent is made by boiling about one pound of castile soap in about two gallons of water. Into this boiling solution, about one quart of ammonia is poured. Then there is quickly added about four ounces of potassium nitrite. When all of the ingredients are dissolved, the composition is allowed to cool. Water is then added until the desired fluidity or thickness is obtained. The cleanser is then ready to be bottled. Heretofore, potassium nitrate and ammonia and castile soap and water have been used in similar preparations. In the past, potassium nitrate has been better known in the arts than potassium nitrite, but in the relatively recent past better and cheaper ways for the production of potassium nitrite have been discovered, which make it possible to obtain the advantages of

using potassium nitrite in a compound such as this instead of potassium nitrate without 55 too greatly enhancing the cost.

Formerly, castile soap was dissolved in boiling water and then potassium nitrate added. Then the solution was allowed to cool. This took a great amount of time, 60 and ammonia was not added until after the solution was cooled. This was because, if the ammonia was added while the solution was hot, the heat would volatilize the ammonia and drive the same off.

In the preparation of the detergent that constitutes the present invention, a great deal of time is saved because all the ingredients are boiled together. In the old practice, a mixture rather than a compound results, inasmuch as potassium nitrate is a very stable compound and, therefore, can not be easily broken down. Potassium nitrite, however, is much less stable and, for that reason, broken down and disintegrated 70 more readily. Therefore, when the castile soap, ammonia, and potassium nitrite are boiled together, the potassium nitrite disintegrates and some of the potassium acts upon the soap, making it semi-soft, while the 80 other freed ingredients act upon the ammonia, forming ammonium nitrite, which, in conjunction with the soap and water, gives the especial cleansing properties to this present detergent, the superiority of 85 which has been determined in actual use and comparison.

It is, of course, to be understood that the quantities mentioned above may be varied and that those mentioned merely indicate 90 substantially the proportions to be used. In case larger amounts of the compound are to be manufactured, the quantities of the ingredients will be correspondingly increased.

To use the said cleaning compound, pour a small quantity on the surface to be cleaned and rub until suds appear. Allow it to stand for a few seconds, and then wash out the soap with water. For removing paint 100 stains, apply in the same manner. For grease on the skin (human cuticle), apply undiluted. To clean kitchen towels and utensils, dilute the cleanser to about four times its volume and boil the articles to be 105 cleaned in such solution.

I claim:

1. A detergent composed of castile soap, ammonia, and potassium nitrite.
2. A detergent composed of castile soap, 5 ammonia, potassium nitrite, and a vehicle.
3. A detergent composed of ingredients compounded in substantially the following proportions: one pound (1 lb.) of castile soap; one quart (1 qt.) of ammonia; four 10 ounces (4 oz.) of potassium nitrite; and water.
4. The herein-described process of making a detergent consisting in boiling about one pound (1 lb.) of castile soap in about two 15 gallons (2 gal.) of water and mixing therewith, while thus boiling, about one quart (1 qt.) of ammonia and then adding thereto about four ounces (4 oz.) of potassium nitrite.
5. The herein-described process of making 20 a detergent consisting in boiling about

one pound (1 lb.) of castile soap in about two gallons (2 gal.) of water and mixing therewith, while thus boiling, about one quart (1 qt.) of ammonia and then adding thereto about four ounces (4 oz.) of potassium nitrite, then allowing the ingredients to dissolve and, thereafter, the compound to cool.

6. The herein-described process of making a detergent consisting in boiling about one pound (1 lb.) of castile soap in about two gallons (2 gal.) of water and mixing therewith, while thus boiling, about one quart (1 qt.) of ammonia and then adding thereto about four ounces (4 oz.) of potassium nitrite, then allowing the ingredients to dissolve and, thereafter, the compound to cool, and then fluidifying with water.

In testimony whereof I hereunto affix my signature.

SIDNEY A. HARTMANN.
